BEAM CHANGER FOR INCANDESCENT
SEARCHLIGHTSWinterton J. Day, Alplaus, N. Y., assignor to
General Electric Company, a corporation of
New York

Application November 26, 1937, Serial No. 176,770

6 Claims. (Cl. 240—44.25)

My invention relates to lamp positioning devices, and more particularly to lamp positioning devices in projectors in which the characteristic of the beam is changed responsive to changes in position of the lamp.

5 One object of my invention is to provide a simple device responsive to successive energizations of the lamp for sequentially positioning said lamp at a plurality of predetermined operating positions without injury to the lamp.

10 For a better understanding of my invention together with other and further objects thereof, reference is had to the following description taken in connection with the accompanying drawings, 15 and its scope will be pointed out in the appended claims.

15 In the accompanying drawings, Fig. 1 is a front elevation in perspective of a lamp and positioning device built in accordance with my invention; Fig. 2 is a sectional view of the device; and Figs. 3, 4, 5 and 6 are diagrammatic views illustrating the lamp in its several positions respectively.

20 Referring to the drawings in detail, Fig. 1 discloses a lamp 10 mounted in a socket 11. The socket is attached to a bracket 12 which is mounted on the end of a shaft 13. The shaft is pivoted in a block of insulating material 14 and in a base plate 15 which is preferably of a non-magnetic metal. This shaft carries an armature 16 rigidly attached to the shaft, and a second armature 17 movable relatively to the shaft between two positions and being held in either position by a friction device. The armature 16 25 is held in an intermediate position between two field poles 18 and 19 by a spring 20. The field poles 18 and 19 are respectively attached to the end of a magnet coil 21 by a bolt 22.

25 As stated above, the armature 16 is held in an intermediate position between the field poles 18 and 19 by a spring 20. This spring is an ordinary helical spring wound about the shaft 13 and having its ends engaging opposite sides of a stationary pin 23. A pin 24 attached to the armature 19 is positioned between the ends of the spring beyond the pin 23 so that when it moves in either direction, it carries with it one end of the spring while the other end is held stationary by the pin 23, thereby placing the spring 30 under an increased tension and providing a force to return the armature to its normal position when the field coil is deenergized. The armature 16 is an elongated magnetic metal member which is, as stated above, normally held in an intermediate position between the field poles 18 and

35 19. This intermediate position is the position at which the armature is parallel to the field poles. When the magnet coil is energized and the field poles, as a result of this energization, tend to attract the armature so as to establish a 5 low resistance magnetic path, the force exerted upon the armature itself is such that no torque is exerted thereon. For the purpose of providing such torque, the second and movable armature 17 is provided. This movable armature 17 10 is also an elongated metallic member, preferably of soft iron, having its ends slightly broadened. It is arranged to have its axis at an angle to the axis of the armature 16. For this purpose, pins 25 and 26 are provided at one end of the 15 armature and spaced from each other sufficiently to permit a substantial angular movement of the armature 17 relatively to the armature 16. In order to keep the armature in any position to which it is moved, a friction device comprising 20 a spring 27 adjustable by a set screw 28 is provided in the armature 17 to exert pressure against the shaft 13. When this armature is moved to its one extreme position, determined by pin 25 25 which engages the armature 16, for example, 30 the angular relationship between the two armatures is such that the pin end of the armature 17 will be nearer to the field pole 19 and will be attracted thereby and the other end will be nearer to and will be attracted by the pole 18, 35 thereby providing a clockwise movement of the armatures upon the energization of the magnet 21. If under these conditions the same relative position of the second armature were maintained, the armature 17, and consequently, the shaft 13 40 would be successively moved clockwise at each energization of the magnet 21. In order to provide for an opposite movement of the shaft 13, however, the armature 17 is further provided with a leaf spring 30 which engages a pin 31 45 on the field pole 19 when the armature 16 is attracted to its extreme position. This engagement of the leaf spring 30 with the pin 31 then holds the armature 17 while armature 16 moves to its operating position so that it will change 50 its relative position to the armature 16 until the pin 26 engages this armature. Upon deenergization of the magnet coil 21 and a return of the armatures to normal position, the pin end of the armature 17 will be nearer to the field pole 55 18, and upon reenergization of the coil 21, a torque will be exerted by the field poles to move the armatures 16 and 17 counterclockwise. A pin 32 is provided on this field pole 18 similar to the pin 31 on pole 19 for again changing the 55

angular relationship between the armatures, and therefore upon reenergization of the coil 21, the armatures will be moved clockwise to their first position.

5 In Fig. 2, the base 33 of the lamp 10 is illustrated above the socket 11 which is arranged to clamp the two prongs 34 and 35 of this base. The socket includes a block 36 of insulating material mounted on the end of the bracket 12 which supports two V-blocks 37 and 38 spaced from each other to correspond to the spacing of the prongs 34 and 35. These V-blocks are attached to the insulating block in any convenient manner, for example, by means of studs (not shown) projecting through the block 36. Strips 39 and 40 of sheet metal are clamped respectively at one end under the V-blocks and are folded over the side of the blocks to the front thereof and are there attached to opposite sides of an insulating block 41. This insulating block is held in spaced relation to the V-blocks by the resiliency of the strips which are preferably of hard copper but may be moved towards the blocks by a thumb nut 42 threaded on a stud 43 mounted in the block 36 and projecting through the block 41. By turning this nut, the block is moved inwardly, moving the strips towards the V-blocks and clamping the prongs of the lamp in position in the notches of the V-blocks.

30 Current is carried to the V-blocks by terminal strips 44 and 45, also attached at one end under the V-blocks respectively, and terminating at the respective other ends in contacts 46 and 47 arranged above one another and above the end 35 of the shaft 13 on the axis of the latter. Co-operating contacts 48 and 49 carry current to these contacts through conductors 50 and 51 and through a switch 52 from any convenient source 53. The coil 21 is connected to the conductors 40 50 and 51, and is therefore simultaneously energized with the socket contacts when the switch 52 is closed.

45 In Figs. 3, 4, 5, and 6, a plan view, partly diagrammatic, of the relationship of the field poles, armatures, and the lamp socket is illustrated in a complete operating sequence. In Fig. 3, the socket is shown in its normal position in which it is held by the spring 20. In this position the socket is in perpendicular relation to a reflector 54. The prongs of the lamp are also held in spaced relation to the axis of rotation, thereby throwing the weight of the lamp off center. In order to compensate for this, a counter weight 55 (see Figs. 1 and 2) is attached to the bracket 12. 50 The armatures 16 and 17 in this Fig. 3 are in such relation that the armature 16 is parallel to the field poles 18 and 19, and the armature 17 is turned counter-clockwise thereof, so that its pin end projects towards the field pole 18 and its 55 opposite end toward the field pole 19, thereby creating a torque, as indicated by the arrow, tending to turn the assembly in a counter-clockwise direction.

60 Fig. 4 discloses the position of the armatures and socket resulting from a closure of switch 52 and an energization of the coil 21. The armature 16 has turned counter-clockwise from the position shown in Fig. 3, and is in the position of the least magnetic resistance path, in which it is held 65 as long as the coil 21 is energized. The armature 17 has, however, turned to its second position in the clockwise direction of the armature 16 by action of the spring 30 engaging the pin 32 on the field pole 18. The socket in this figure is parallel 70 to the reflector 54, and is spaced between the

shaft 13 and the mirror. In this position, the lamp 10 is in its first operating position with its filament 56 in focus with this reflector, and therefore, in position to throw a concentrated or narrow beam. The filament 56 is arranged in a plane 5 and in this position, the plane is perpendicular to the axis of the reflector, thereby presenting its maximum area to the reflector.

Fig. 5 discloses the position of the armature and socket immediately following deenergization of the coil 21 subsequent to the energization disclosed in Fig. 4. In this figure, the socket 11 has returned to its normal position as illustrated in Fig. 3, but the relationship of the armatures 16 and 17 has changed from that illustrated in Fig. 15 3, so that the pin end of the armature now is nearer to field pole 19, and the opposite end of this armature is nearer to the field pole 18, thereby tending to rotate the armature clockwise, as indicated by the arrow, upon the reenergization 20 of the coil 21.

Fig. 6 illustrates the position of the armatures as a result of an energization of the coil 21 subsequent to a positioning of the armatures as illustrated in Fig. 5. In this position, the spring 25 30 has engaged a pin 31 on the field pole 19, and has again returned the armature 17 to that position shown in Fig. 3. The socket in this instance holds the prongs of the lamp on the outside of the shaft 13; that is, the side opposite to the 30 mirror, and thereby holds the lamp in its second operating position with its filament out of focus of the reflector. In this position, the light from the reflector is scattered, and a broad beam is projected by the mirror.

35 One important advantage of this device, is that the lamp is moved from one position to another without any serious shock which would tend to injure the filament. When the armature is attracted by the field poles against the tension 40 of the spring 20, a gradual increase in the torque of the spring is obtained, and when the spring 30 touches the pins 31 and 32, it is also placed under strain tending to stop the armature 16 in its final position without oscillations. Since this 45 force tending to stop the armature is built up so gradually, substantially no shock occurs which might injure the filament.

50 In accordance with the provision of the patent statute, I have described the principle of operation of my invention, together with the apparatus which I now consider to represent the best embodiment thereof; but I desire to have it understood that the apparatus shown is only illustrative, and that the invention may be carried 55 out by other means.

What I claim as new and desire to secure by Letters Patent in the United States is:

1. In a positioning device, the combination of a pivoted support and means for sequentially moving said support to a plurality of predetermined positions about its pivot, said means including an electromagnet provided with a pair of field poles, an armature mounted rigidly on said support, means for normally holding said armature in a position intermediate said field poles whereby upon energization of said electromagnet the torque upon said armature is equal and opposite, and means for unbalancing this torque and thereby initiating a movement of said 60 armature responsive to energization of said electromagnet, said unbalancing means being operated at each operating movement of said armature for effecting a movement of said armature to predetermined succeeding positions respective- 65 70 75

ly responsive to successive energizations of said electromagnet.

2. In a positioning device, the combination of a pivoted support and means for sequentially moving said support to a plurality of predetermined positions about its pivot, said means including an electromagnet provided with field poles, an armature mounted rigidly on said support, a second armature mounted on said support and movable relatively to said first armature, means for normally holding said support and said armatures in an intermediate position relatively to said field poles, and means operable upon an energization of said field magnet and a corresponding attraction of said armatures to one predetermined position for simultaneously moving said second armature relatively to said first armature whereby upon deenergization of said field coil and a corresponding return to an intermediate position said armatures will be attracted to a predetermined other succeeding position responsive to a succeeding energization of said electromagnet.

3. In a positioning device, the combination of a shaft and means for sequentially turning said shaft to two predetermined operating positions about its axis including an electromagnet provided with a pair of field poles, an armature rigidly mounted on said shaft, a second armature mounted on said shaft and movable relatively to said first armature between two positions, means for normally holding said first armature in a position intermediate said field poles, and means operable upon an energization of said field magnet and a corresponding attraction of said magnets to one of said two predetermined operating positions for moving said second armature relatively to said first armature whereby upon a succeeding energization of said magnet said armatures will be moved to the second of said predetermined operating positions.

4. In a lamp positioning device the combination of a pivoted shaft, a lamp socket mounted on said shaft in spaced relation to the axis of said shaft, means for turning said shaft to position said socket relatively to a reflector including an electromagnet, a pair of field poles, an armature rigidly attached to said shaft and attached by said field poles upon energization of said magnet in either of two positions, means for normally holding said armature in an intermediate position, a second armature movable relatively to said first armature and operable between two positions to determine the operating position to which said first armature is attracted upon energization of said electromagnet, and means oper-

able at each movement of said first armature to an operating position to move said second armature relatively to said first armature whereby the said first armature is sequentially moved to its respective operating positions in response to successive energizations of said magnet.

5. In a lamp positioning device, the combination of a shaft having mounted thereon a lamp support spaced from the axis of said shaft, means for turning said shaft to sequentially position said lamp support in a plurality of operating positions about said shaft axis, said means including a field magnet connected to be energized simultaneously with the said socket, field poles therefor, an armature mounted on said shaft and rigidly attached thereto, a second armature mounted on said shaft and movable relatively to said shaft and said first armature, means for normally holding said first armature in an intermediate position between said field poles, and means attached to said second armature and cooperable with said field poles to move said second armature relatively to said first armature at each energization of said field coil whereby at successive energizations of said field coil said first armature is sequentially moved to a plurality of positions relatively to said field poles and said socket is correspondingly positioned about the axis of said shaft in one of a plurality of operating positions responsive to successive energizations of said field coil.

6. In a lamp positioning device the combination of a shaft, a lamp socket mounted thereon and arranged to support a lamp in spaced relation to the axis of said shaft, means to hold normally said shaft in one position, an armature rigidly mounted on said shaft, an electromagnet provided with a pair of field poles arranged when energized to exert a torque upon said armature and turn said shaft from said normal position to a predetermined operating position on either side of said normal position, and means for sequentially turning said shaft to said operating positions responsive to succeeding energizations of said magnet including a second armature mounted on said shaft and movable between two positions relatively to said first armature and a spring attached to said second armature engaged by said field poles respectively when said first armature moves to an operating position for moving said second armature to an opposite position relatively to said first armature, whereby upon re-energization of said magnet an opposite torque will be exerted thereon and it will move to its other operating position.

WINTERTON J. DAY.
